John J. Kennedy

UNITED STATES PATENT OFFICE.

JOHN J. KENNEDY, OF NEW YORK, N. Y.

METHOD OF BUILDING STRUCTURES.

1,409,729.

Specification of Letters Patent. Patented Mar. 14, 1922.

Application filed August 20, 1921. Serial No. 493,866.

To all whom it may concern:

Be it known that I, JOHN J. KENNEDY, a citizen of the United States, and resident of the borough of Manhattan, in the city and 5 State of New York, have invented a new and useful Improvement in the Method of Building Structures, of which the following is a specification.

This invention relates to a method of 10 building structures and has for its object to provide a method which is inexpensive, speedy in construction, damp proof, substantially fireproof, and economical in the use of materials.

Another object is to provide a method of 15 building structures which is simple in construction and capable of being operated and erected by unskilled labor.

Another object is to provide certain improvements in the form, construction and 20 arrangement of the elements whereby the above named and other objects may be effectively attained.

A practical embodiment of my invention 25 is represented in the accompanying drawings, in which—

Fig. 1 represents a perspective view of a building structure, showing a portion of the roof removed.

Fig. 2 represents a perspective view of the 30 basement and first story in the course of erection, a portion of the forms used and the walls of the story being broken away to show the insertion of the molds for forming 35 doors and windows.

Fig. 3 represents a detail vertical section, on an enlarged scale, of the method of constructing the walls.

Fig. 4 represents a horizontal section 40 taken in the plane of the line IV—IV of Fig. 3.

Fig. 5 represents a detail vertical section of the building structure shown in Fig. 2.

Fig. 6 represents a detail vertical section 45 of the building structure shown in Fig. 1, and

Fig. 7 represents a perspective view of a portion of the means of connection between the walls of the first and second stories.

The building structure which I have 50 shown in the drawings consists of a basement denoted by 1, a first story by 2, a second story by 3, and a roof by 4. The basement 1 is built of concrete or stone in any 55 well-known and approved manner and pro-

vided with an annular groove 5 which serves as a lock joint for the walls of the first story.

The method of building the walls of the first story comprises an inner form 6, an outer form 7, which forms may extend the 60 full length and height of the wall to be built or arranged in sections. These forms are constructed of vertically arranged studs 8 and tongue and grooved sheathing 9 secured horizontally to the studs 8. The walls are 65 made damp proof and fireproof by means of hollow firebricks 10 which are located adjacent the sheathing of the inner form 6. The inner form 6 is held in position by means of temporary braces 11 which are secured be-

tween the studs 8 and the floor beams 12, as 70 shown in Figs. 2 and 5. The outer form is held in position by any well-known and ap-

proved means such, for instance, as wires or bolts, not shown, which engage both the in- 75 ner and outer forms. When the forms and brick lining 10 are in position, a concrete mixture 13 is tamped therebetween filling the groove 5 in the basement wall and pro-

viding a bond with the basement walls. 80 Upon the upper edge of the walls formed between the forms, I insert a plate 14 of wood or other similar material, which is laid horizontally in the wall and secured by depending bolts 15 which are embedded in 85 the concrete forming the wall. After the concrete mixture 13 has set and formed the wall, the outer form 7 is raised upwardly and reversed so that the studs 8 are disposed toward the center of the building and the 90 sheathing exposed exteriorly. The form 7 is secured to the plate 14 by means of bolts 16 which project upwardly from the plate 14 and engage the strip 17 carried by the lower end of the form. Thus it will be seen 95 that the form 7 is utilized as the walls of the superstructure and the sheathing of the forms located so as to be in vertical alignment with the exterior surface of the wall of the first story, so as to receive the outer 100 covering 18, such as clapboard, shingles or other suitable material which will add to the artistic finish of the building structure.

To provide the first story with suitable 105 openings by which windows and doors may be made, I insert between the forms 6 and 7 boxes 19, and locate them in the position desired before the concrete mixture is poured into the forms.

It is to be understood that openings may 110

be cut in the form 7 to provide the superstructure with the desired windows in the usual manner, as indicated in Fig. 1.

The form 6 is utilized to construct the roof for the structure and is secured to a header 20 carried by the form 7 in any well-known and approved manner.

It is obvious that various changes may be resorted to in the form, construction and arrangement of the several parts without departing from the spirit and scope of my invention; hence I do not wish to limit myself to the particular embodiments herein shown and described except as they may be included in the claims.

What I claim is:

1. The method of building structures comprising providing a form, molding the lower walls of a structure within said form, removing said form and utilizing the same for a superstructure, and applying an outer covering for said superstructure.
2. The method of building structures comprising providing a form having sets of inner and outer walls, molding the lower walls of a structure within said form walls, removing said form walls and utilizing the outer set of said form walls as the walls of a superstructure and the inner set of form walls as the material for the roof of said superstructure.

3. The method of building structures comprising providing a form having sets of inner and outer walls, molding the lower walls of a structure within said form walls, removing said form walls and utilizing one set of form walls as the walls of a superstructure, and applying a covering for said walls of said superstructure.

4. The method of building structures comprising providing a form having sets of inner and outer walls, molding the lower walls of a structure within said form walls, removing said form walls and utilizing the outer set of form walls as the walls of a superstructure, and applying a covering for said walls of said superstructure.

5. The method of building structures comprising providing a form having sets of inner and outer walls, molding the lower walls of a structure within said form walls, removing said form walls and utilizing the outer set of form walls as the walls of a superstructure and the inner set of form walls as the material for the roof of said superstructure, and applying a covering for said walls of the superstructure.

In testimony, that I claim the foregoing as my invention, I have signed my name this 19th day of August, 1921.

JOHN J. KENNEDY.
